UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed July 16, 1923. Serial No. 651,894.

To all whom it may concern:

Be it known that I, BYERS W. KADEL, a citizen of the United States, residing at Baltimore, in the State of Maryland, have invented certain new and useful Improvements in Draft Rigging; and I do hereby declare the following to be a full, clear, and exact description of the invention, such as will enable others skilled in the art to which it appertains to make and use the same.

This invention relates to an improved construction for connecting draft gears of the tandem type to railway cars having wooden center sills.

One of the principal features of the invention is to provide a strong, reliable metallic draft arm in which metal reinforcing members and draft sills are applied to a wooden underframe car so as to form a draft rigging pocket which will accommodate a plurality of cushioning members of standard construction disposed so as to increase the capacity of the gear.

Another object of the invention is to provide a metallic draft arm for wooden underframe cars adapted to receive tandem arranged springs and followers, said draft arm being designed in such a manner that the several parts comprising the draft gear already in use on these wooden types of cars can be employed, and additional cushioning means of comparatively inexpensive construction provided whereby the increased draft and buffing strains incident to modern service conditions can be effectively resisted.

A further object of the invention is to provide in combination a draft rigging and metallic construction of draft arm capable of being easily applied to wooden underframe cars and adapted to receive tandem arranged springs and followers, said construction involving reinforcing angle members connected to the wooden center sills and extending well beyond the bolster, depending channels forming draft sills between which the standard springs of the draft gear can be disposed in adjacent parallel and horizontal arrangement to form a part of the tandem gear, an additional spring of relatively large size arranged in tandem relation to the first mentioned part of the cushioning mechanism, a plurality of stop members connected to the draft sills with which the followers of the respective cushioning springs cooperate, a two-part

yoke member rigidly connected to the coupler, and a key connected follower, the excess buffing loads of the gear being received by said key and transmitted to the center sills.

The invention further consists in the combination and arrangement of the several parts hereinafter to be described.

In the drawings illustrating the invention, the scope whereof is pointed out in the claims:

Figure 1 is a top plan view of my improved construction of draft rigging and associated parts as applied to a wooden underframe car, a portion of the figure being shown in horizontal section.

Figure 2 is a vertical longitudinal sectional view of the construction shown in Figure 1, some of the parts being shown in side elevation.

Figure 3 is a transverse vertical sectional view on the line 3—3 of Figure 2 viewed in the direction of the arrows.

Figure 4 is a transverse vertical sectional view on the line 4—4 of Figure 2, viewed in the direction of the arrows.

Figure 5 is a plan view partly in section of a modified construction of my invention as applied to a wooden underframe car, portions being shown in horizontal section.

Figure 6 is a vertical longitudinal sectional view of the construction shown in Figure 5, certain of the parts being shown in elevation.

Figure 7 is a transverse vertical sectional view on the line 7—7 of Figure 6, viewed in the direction of the arrows.

Figure 8 is a transverse vertical sectional view on the line 8—8 of Figure 6, viewed in the direction of the arrows.

Referring to the drawings in which corresponding reference characters designate similar parts in the several views, wooden center sills 1 are reinforced by means of longitudinally extending angle members or bars 2, said reinforcing angle bars being connected to the center sills by means of the transverse bolts 3 and the vertical bolts 4. The angle bars 2 are adapted to extend from the end sill 5 to a point well beyond the bolster 6, as clearly shown in Figures 1 and 2. A striking block 7 is shown adjacent the end sill 5, it being suitably connected thereto by means of bolts 8.

Depending from the reinforcing angle

bars 2 are the draft sills 9, said draft sills being shown in the form of channels, the upper web of which is adapted to be riveted to the horizontal web of the angle bar and 5 further secured to the center sills by means of the vertically disposed bolts 4. The draft sills are adapted to extend from the front end of the striking block to a point immediately in front of the bolster 6, said 10 draft sills being united at their front ends by means of a carry iron 10. The draft sills, carry iron and striking block are adapted to be united by the vertically disposed bolts 11, the innermost of said bolts being adapted 15 to extend through spacing and supporting members 12 arranged adjacent the inner faces of the draft sills, as best shown in Figure 8.

The coupler 13, and more especially the 20 shank thereof, is shown supported upon the carry iron 10, said coupler being rigidly connected by means of rivets 14 to the two-piece yoke 15. The yoke is of the vertical type and comprises two parts 16 and 17, 25 respectively. The arms of the portion 17 of the yoke are adapted to overlie and underlie, respectively, the arms of the part 16 of said yoke, said overlapped portions being connected by means of rivets 18 adapted to 30 pass through the thimble block 19 separating the yoke into two parts for cooperation with the tandem arrangement of springs and followers. In practice the yoke parts 16 and 17 may be formed by cutting the present type 35 of one-piece yoke into the two sections, thereby permitting the adaptation of the yoke already in use on the car to the present embodiment of the invention.

The cushioning mechanism comprises tandem arranged springs and followers, a twin arrangement of springs 20 being shown by the dot and dash lines in Figures 1 and 2, and a single arrangement of spring 21 being similarly indicated in said figures. The twin 40 springs 20 are positioned in the forward portion of the draft rigging pocket between the draft sills which are offset with relation to the inner opposed faces of the center sills to provide the relatively wide pocket, 45 and as shown. Each of the springs used in the twin arrangement is of a capacity equal to that of the heretofore tandem arrangement in the old construction of wooden under-frame and draft rigging pocket. The single 50 spring 21 is preferably of a relatively larger capacity than the springs 20, thereby materially increasing the total capacity of the cushioning mechanism. The front and rear 55 followers, respectively, of the rear spring 21, are indicated by the numerals 22 and 23, said followers being adapted to cooperate with stop lugs projecting inwardly from stop members 24 connected to the inner faces of the draft sills. The front stop lugs 60 are indicated by the numeral 25 and the rear 65

stop lugs are indicated by the numeral 26. The stop members 24 are suitably reinforced by horizontally and vertically disposed ribs 27 uniting the respective stop lugs 25 and 26 with the body portion of the stop member. 70 The followers 22 and 23 are adapted to co-act with adjacent portions provided on the yoke, as will be understood.

Each stop member 24 is also provided with an inwardly projecting stop lug 28, 75 said stop lugs 28 providing the rear stop members for the rear follower 29 of the front twin springs. The stop lugs 28 are suitably reinforced by longitudinally extending ribs 30 which unite said lugs with 80 the side wall or body portion of the stop member and the intermediate stop lug 25.

The front follower of the twin springs is indicated by the numeral 31, said follower having passing therethrough a key 32, the 85 respective ends of said key projecting through slotted portions of the draft sills and being adapted to co-act with stop portions provided on the cheek plates or stop members 33. The front follower is formed 90 with vertically disposed and transversely arranged webs providing the front and rear faces thereof, said webs being longitudinally united by a plurality of vertically disposed webs 31^a. The follower extends 95 substantially the full width of the draft rigging pocket and is adapted to contact the rear face of the coupler butt. The cheek plates 33 are connected to the outer faces 100 of the draft sills and are provided with stop portions against which the edges of the key strike when the cushioning mechanism goes solid, the excess load incident to the buffing movement being imparted to the underframe through the key which is placed 105 under shear in receiving such excess loads. The followers of the twin spring arrangement are each provided with spring retaining lugs 34.

The rear end of the yoke is preferably 110 supported upon the cross plate 35, said plate being connected to the lower faces of the draft channels by means of bolts 36. A top tie member 37 is preferably provided 115 for the reinforcing angle bars 2, said tie member being connected to said bars by means of rivets 38. The forward ends of the reinforcing angle bars are also suitably connected by means of a plate 39 arranged adjacent the end sill 5, said plate being 120 connected to the reinforcing bars by means of rivets 40.

The modified form of my invention illustrated in Figures 5 and 6 includes the several parts hereinbefore described with the exception of the key-connected follower cooperating with the front follower of the twin springs 20. In this modified construction front stop members or lugs 41 are provided 125 upon the inner opposed faces of the draft 130

sills 9, said stop lugs being connected to said sills by means of rivets 42. The stop lugs 41 may be reinforced by means of webs 43, as shown. The front and rear followers 5 of the twin springs are indicated by the numerals 44 and 45, respectively, said followers being of the plain face type, as shown.

The forward portion of the yoke is supported upon the cross plate 46, said cross plate being connected to the underfaces of the draft sills by means of bolts 47 and suitably shaped to support the respective twin springs 20, as clearly shown in Figure 7.

A draft rigging and underframe construction formed in accordance with my present invention permits of the replacing of the old wooden draft sills or timbers by a metallic draft arm which provides an adequate draft rigging pocket capable of receiving a tandem arrangement of springs and followers of relatively increased capacity. It will be obvious that the yoke now in use can be economically cut and connected as hereinbefore referred to and also it will be observed that the usual or standard springs 30 hereinbefore arranged in tandem can be associated in twin horizontal arrangement. The additional cushioning capacity of the gear is therefore obtained at comparatively inexpensive cost, the stop members being preferably cast and capable of easy attachment to the draft sills.

Having now fully described my invention, although it is to be understood that the terms are to be taken in their descriptive sense and not in their limiting sense, what I claim and desire to secure by Letters Patent, is:

I claim:

1. In a railway draft rigging, the combination with a wooden underframe car having wooden center sills, of metallic reinforcing means for each of said center sills, a depending metallic draft sill connected to each adjacent center sill, said draft sills being spaced apart sufficiently to receive horizontally arranged twin springs adapted to form a part of the cushioning mechanism, a single spring disposed in tandem arrangement with respect to the first named springs, a plurality of followers for said springs, a plurality of stop members connected to said draft sills and cooperating with said followers, a coupler, and a two-part yoke having portions cooperating with said followers.

2. In a railway draft rigging, the combination with a wooden underframe car having wooden center sills, of metallic reinforcing means for said center sills, metallic draft sills connected to the center sills, said draft sills being offset from the inner opposed faces of the center sills to provide a relatively wide draft rigging pocket, a plurality of springs disposed in twin arrangement in the front end of said pocket, an ad-

ditional spring positioned in said draft rigging pocket in tandem relation to the first named springs, a coupler, a yoke rigidly connected to said coupler, a plurality of tandem arranged followers adapted to contact portions of said yoke, and a plurality of stop members cooperating with said followers, said stop members being connected to the draft sills.

3. In a railway draft rigging, the combination with a wooden underframe car having wooden center sills, end sills and bolster, a metallic reinforcing means for said center sills, draft sills connected to said reinforcing means and to said center sills, said draft sills being spaced apart a greater distance than said center sills, cheek plates connected to the inner faces of said draft sills, said plates each having front and rear stops shoulders, independent stop members connected to said sills forwardly of said cheek plates, tandem arranged springs and followers, one pair of said followers being substantially equal in width to the distance between said draft sills, a coupler, and means for operatively connecting said coupler to said tandem arranged springs.

4. In a railway draft rigging, the combination with a wooden underframe car having wooden center sills, of metallic reinforcing means for said center sills, a metallic draft sill depending from each of said center sills, said draft sills providing a relatively wide draft rigging pocket, a cushioning mechanism involving tandem arranged springs and followers, a key passing through one of said followers, stop members provided on the outer faces of the draft sills adapted to co-act with said key, stop members each comprising connected front and rear stop shoulders for the other of said followers, said last named stop members being connected to the draft sills, a coupler cooperating with the follower through which the key passes, and a yoke rigidly connected to said coupler.

5. In a railway draft rigging, the combination with a wooden underframe having wooden center sills, of a reinforcing metallic member connected to each of said center sills, a depending metallic draft sill connected to said center sills, a cushioning mechanism comprising a two-part yoke, tandem arranged springs and followers, a key passing through one of said followers, stop members provided on the inner faces of the draft sills and adapted to co-act with some of said followers, and stop members provided on the outer faces of said draft sills having portions adapted to co-act with said key.

6. In a railway draft rigging, the combination with center sills, draft sills connected to said center sills, a coupler, a two-part yoke rigidly connected to said coupler, a

tandem arranged cushioning mechanism comprising front twin springs and followers and a rear spring and followers, stop members connected to the inner opposed faces of said draft sills, each of said stop members having portions providing stops for the followers of the single spring and one of the followers of the twin springs, stop

members provided on the outer faces of the draft sills, and a key connected to the other follower of the twin springs, said key projecting through the draft sills and being adapted to co-act with the stop members connected to the outer faces thereof.

In testimony whereof I affix my signature.

BYERS W. KADEL.
